FORM GRINDING APPARATUS

Carl G. Flygare, Worcester, Mass., assignor to
 Norton Company, Worcester, Mass., a corporation of Massachusetts

Application December 12, 1938, Serial No. 245,203

5 Claims. (Cl. 51—100)

The invention relates to grinding machines, and more particularly to a form grinding attachment therefor.

One object of the invention is to provide a cylindrical grinding machine with a form grinding attachment which is simple and thoroughly practical in construction and which is applicable to any of the standard cylindrical grinding machines. Another object of the invention is to provide a form grinding attachment for a cylindrical grinding machine whereby a visible indicating device serves to enable the operator to coordinate the manual traverse of the work table and the manual feeding of the grinding wheel to produce a predetermined form on the work piece. A further object of the invention is to provide a form grinding attachment comprising a forming bar having a pivotally mounted, transversely movable follower which is provided with a pair of dial indicators to facilitate coordinating the manual traverse of the work table and the manual feeding of the grinding wheel to reproduce the form or shape on a work piece. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiment of the mechanical features of this invention,

Fig. 1 is a right-hand end elevation of a cylindrical grinding machine embodying the improved form grinding attachment, having part of the base broken away and part shown in section to more clearly illustrate the machine structure;

Fig. 2 is a fragmentary end elevation, on an enlarged scale, of the forming device;

Fig. 3 is a fragmentary plan view, on an enlarged scale, of a cylindrical grinding machine embodying the improved forming attachment; and

Fig. 4 is a fragmentary plan view, on an enlarged scale, of the forming device and footstock.

A cylindrical grinding machine has been illustrated in the drawings having a base 10 which supports a longitudinally movable work supporting table 11 on the usual V-way 12 and flat way 13 formed on the upper surface of the base 10. A rotatable grinding wheel 15 is supported on one end of a wheel spindle 16 which is rotat-

ably supported in a transversely movable wheel slide 17. The wheel slide 17 is mounted on suitable ways, such as a flat way and a V-way (not shown) formed on the upper surface of the base 10. The grinding wheel 15 and the wheel spindle 16 may be rotated by any suitable driving mechanism, such as a pulley 18 mounted on the end of the spindle 16 which is connected by means of a multiple V-belt 19 with a suitable source of power (not shown).

The grinding wheel slide 17 is arranged to be moved transversely by means of a wheel feeding mechanism comprising a rotatable feed screw 20 rotatably supported in bearings within the base of the machine. A half nut 21 is fixedly mounted to the under surface of the wheel slide 17 and meshes with the feed screw 20. The forward reduced end portion 22 of the feed screw 20 is slidably keyed within a hollow sleeve 23 which is rotatably journaled in a bearing 24 in the base of the machine. A cylindrical shaft 25 is formed integral with the sleeve 23 and has a bearing 26 in the base of the machine. A gear 27 is mounted on the outer end of the shaft 25. The gear 27 meshes with a gear 28 which is formed integral with a sleeve 29 which supports a manually operable feed wheel 30. The feed wheel 30 and its associated parts above described are substantially identical with the wheel feeding mechanism shown in the expired patent to Norton No. 762,838 dated June 14, 1904, to which reference may be had for details of disclosure not contained herein.

A traversing mechanism is provided for traversing the work supporting table 11 longitudinally relative to the base 10. This mechanism may comprise a rack bar 35 depending from the under side of the table 11 which meshes with a gear 36 mounted on the inner end of a shaft 37 rotatably supported in a bearing 38 in the base 10 of the machine. A manually operable hand wheel 39 is mounted on the outer end of the shaft 37 by means of which the gear 36 may be rotated and the table 11 traversed longitudinally.

A work piece 45 to be ground is supported by a headstock center 46 and a footstock center 47. The headstock center 46 is carried by a headstock 48 (Fig. 3) which is adjustably supported on the table 11 in the usual manner. The footstock center 47 is supported by a footstock 49 which is adjustably mounted on the table 11. A manually operable adjusting wheel 50 is provided longitudinally to adjust the position of the footstock center 47 so as to withdraw the same to remove a finish ground work piece and to move it

into operative engagement with a new work piece after it has been inserted within the machine.

5 A forming bar or template 52 is supported by a bracket 53 which is supported on the upper surface of the footstock 49. The forming bar or template 52 is provided with an irregularly shaped surface 54 which corresponds with the shape which it is desired to produce on the periphery of the rotatable work piece 45.

10 A pivotally mounted transversely movable follower 60 is provided which engages the surface 54 of the template 52. The periphery of the grinding wheel 15 is preferably shaped to correspond with the shape of the follower 60. The follower 60 is pivotally supported by means of a stud 61 which is carried by member 62. The member 62 is slidably supported within a bracket 63 which is adjustably fastened onto the upper 15 surface of the wheel slide 17. The member 63 is provided with an elongated slot 64 through which pass a pair of adjusting screws 65 and 66. These screws are screw threaded into the upper surface of the wheel slide 17 and serve adjustably to position the member 63 in a transverse direction.

15 The pivotally mounted follower 60 is preferably formed integral with an enlarged head 67 which is pivotally supported by means of the vertically arranged stud 61 which is fastened to the forward end of the transversely movable slide member 62. A guide stud 68 is supported by the pivotally mounted member 67 and is provided at its upper end with a reduced diameter stud which slides 20 within an elongated arcuate slot 69 formed in the transversely movable slide member 62. The elongated slot 69 together with the guide stud 68 serves to limit the swinging movement of the follower member 60. The follower member 60 together with its enlarged supporting member 67 is preferably held in a central position by means of a spring actuated mechanism. The enlarged portion 67 of the follower member 60 is provided with a pair of spaced pins 72. The transversely movable slide member 62 is also provided with a pair of spaced pins which are spaced equi-distant to the spacing of the pins 72. A compression spring 14 is contained within the telescopic tubular members 75 and 76. The outer end of the tubular member 75 is provided with a V-shaped end 77 which engages the pins 73 and 72. The tubular member 76 is similarly provided with a V-shaped end surface 78 which is arranged to engage the pins 73 and 72, respectively, on the opposite side of the slide member 62. The pins 73 are fixedly mounted on the transversely movable slide 62 and remain in fixed positions except for the transverse movement.

25 The enlarged portion 67 of the follower member 60 is free to swing about the stud 61 as a pivot and such swinging movement, through the spaced pins 72, serves further to compress the spring 14. The spring 14, however, serves normally to exert a pressure tending to return the follower 60 to a normal or central operating position. A dial indicator 80 is mounted on the transversely movable slide member 62. The dial indicator is provided with an actuating plunger 81 which is arranged in the path of an adjusting screw 82 which is in turn screw threaded in a bracket 83. The bracket 83 is fixedly bolted to the enlarged portion 67 of the follower member 60. When the follower 60 is in a balanced or central position, that is, out of engagement with the template 52, the adjusting screw 82 is

30 turned to set the dial indicator so that the needle reads zero. After this setting of the dial indicator, any deflection of the follower 60 will produce a rocking movement of the enlarged head portion 67 which will transmit this motion 35 through the adjusting screw 82 to cause a movement of the dial indicator plunger 81 so that the dial indicator will read either in ten thousandths of an inch or otherwise depending on the nature of the dial gauge. The extent of deflection of the follower 60 is visibly indicated on the dial gauge 80.

35 The transversely movable slide member 62 has a rearwardly extending portion which is substantially rectangular in cross sectional area and 40 which slides within an aperture 85 (Fig. 2) within the enlarged end portion 86 of the transversely arranged supporting member 63. A compression spring 87 contained within the aperture 85 serves normally to exert a pressure toward the left (Fig. 20 2) to urge the slide 62 toward the left so as to maintain the follower 60 in operative engagement with the template 52 during the longitudinal movement thereof. A dial indicator 88 is supported by the transversely movable slide 62 and 25 is provided with an actuating plunger 89. The transversely adjustable supporting member 63 is provided with a bracket 90 which supports an adjusting screw 91 which is arranged in alignment with the plunger 89 of the dial indicator 80. 30 The adjusting screw 91 serves to facilitate adjustment of the dial indicator 88 so that a zero reading may be readily obtained in setting up the forming apparatus.

35 In the operation of this improved form grinding apparatus, the transverse slide 63 is adjusted transversely so that the follower 60 is in engagement with the operative face of the forming bar when the follower 60 is at a most forward position in its path of movement. The transverse 40 adjustment of the slide 63 is sufficient to compress the spring 87 to maintain the follower 60 in operative engagement with the operative surface 54 of the template 52. The adjusting screws 82 and 91 are then adjusted so that the dial indicators 80 and 88 45 respectively read zero. The machine is then in adjusted position for a grinding operation. A work piece 45 is placed on centers 46 and 47 and a suitable driving dog is provided so that the rotary movement of the headstock is transmitted to rotate the work piece 45 for a grinding operation. The hand feed wheel 30 is then rotated to move the grinding wheel 15 and its supporting slide 17 transversely into operative engagement 50 with the work piece 45, at which time the hand traverse wheel 39 is rotated to start a longitudinal traversing movement of the work piece 55 relative to the grinding wheel.

55 By controlling the longitudinal movement of the table 11 and the transverse movement of the wheel slide 17 by means of the hand wheels 30 and 39, respectively, so that the dial indicators 80 and 88 respectively read zero during the entire pass of the work piece across the face of the wheel, 60 an exact duplication of the shape of the surface 54 of the template 52 will be obtained. During the longitudinal movement of the work table 11, which in turn carries the template 52 therewith, excess longitudinal movement of the table 65 will cause a pivotal deflection of the follower 60 which will be readily visible on the dial indicator 80. Similarly, an excess movement of the transverse movement of the wheel will be indicated on the dial indicator 88. By manually coordinating 70 75

the manual rotation of the hand wheels 30 and 39, the table and wheel will be moved longitudinally and transversely respectively to reproduce a shape of the desired and predetermined extent.

By changing the shape of the bar or template 52, any desired shape on the work piece may be produced. The template 52 is preferably adjustably mounted (Fig. 3) and is located in a definite position relative to the work piece 45 so that the relation between the follower 60 and the template surface 54 corresponds with the relationship between the work piece 45 and the operative face of the grinding wheel 15. It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a rotatable grinding wheel and a rotatable work support which are movable longitudinally and transversely relative to each other, a visible indicating form grinding attachment including a template and a pivotally mounted transversely movable follower one of which is mounted to move with the grinding wheel and the other to move with the work support, and means including a dial indicator which is actuated by said follower to register relative pivotal and transverse movements of said follower during the relative longitudinal and transverse movements of the grinding wheel and work support to facilitate grinding a predetermined form on the work piece.

2. In a grinding machine having a base, a rotatable grinding wheel, a transversely movable slide therefor, a feeding mechanism including a manually operable feed wheel to move said slide and wheel transversely in either direction, a longitudinally movable table, a manually operable traverse mechanism including a hand wheel to traverse the table longitudinally in either direction, a rotatable work support on said table, and a forming attachment therefor including a forming bar, a transversely movable pivotally mounted follower and an indicator associated therewith which serve to register movements of said follower during the relative longitudinal and transverse movements between the grinding wheel and work support whereby coordinated actuation of

the traverse and feeding mechanisms serves to grind a predetermined form on said work piece.

3. In a grinding machine having a rotatable grinding wheel and a rotatable work support which are movable longitudinally and transversely relative to each other, a visible indicating form grinding attachment including a forming bar and a pivotally mounted transversely movable follower one of which is movable with the grinding wheel and the other movable with the work support, a dial indicator which serves to register relative pivotal movement of said follower, and a second dial indicator which serves to register transverse movement of said follower during the relative longitudinal and transverse movements of the grinding wheel and work support to facilitate grinding a predetermined form on the work piece.

4. In a grinding machine having a base, a rotatable grinding wheel, a transversely movable slide therefor, a manually operable feeding mechanism for the wheel and slide, a longitudinally movable table, a manually operable traverse mechanism to traverse said table longitudinally in either direction, a rotatable work support on said table, and a visible indicating form grinding attachment therefor including a forming bar supported by said table, a transversely movable pivotally mounted follower adjustably supported by said wheel slide, and an indicator associated with said follower which serves visibly to register relative pivotal and transverse movements of said follower during relative longitudinal and transverse movements of the grinding wheel and work support to facilitate grinding a predetermined shape on the work piece.

5. In a grinding machine having a base, a rotatable grinding wheel, a transversely movable slide therefor, a feeding mechanism including a manually operable feed wheel to move said slide and wheel transversely in either direction, a longitudinally movable table, a manually operable traverse mechanism therefor to traverse the table longitudinally in either direction, a rotatable work support on said table, and a visible indicating form grinding attachment including a template supported by said table and a pivotally mounted transversely movable follower adjustably supported by said wheel slide, a dial indicator which serves to register relative pivotal movement of said follower, and a second dial indicator which serves visibly to register relative transverse movements of said follower during coordinated relative longitudinal and transverse movements between the grinding wheel and work support to facilitate grinding a predetermined form on a work piece.

CARL G. FLYGARE.
